UNITED STATES PATENT OFFICE

STANLEY W. NICHOLSON, OF MILWAUKEE, WISCONSIN, ASSIGNOR TO BRIGGS & STRATTON CORPORATION, OF MILWAUKEE, WISCONSIN, A CORPORATION OF DELAWARE

WINDOW REGULATOR

Application filed October 28, 1931. Serial No. 571,516.

This invention relates to window regulators and more particularly to window regulators of the link type in which the window is raised and lowered through a series of levers and links.

It is an object of the present invention to devise a window regulator which will raise and lower the window parallel to itself so as to prevent binding between the window casing and the window.

It is a further object of the invention to provide means for readily attaching or detaching a window from the window regulator.

Another object of the invention is to provide a simple window regulator with a minimum number of moving parts which may be readily attached in place and which will effect positively parallel movement of the pane, and other objects will become apparent as the description proceeds.

A structure embodying the invention is illustrated in the accompanying drawings and will be hereinafter fully described, the invention residing in certain novel features which will be particularly pointed out in the appended claims.

In the drawings:

Figure 1 is an elevational view of a window regulator in place in the door, parts of the door being broken away to more clearly illustrate the invention, the window being shown in lowered position;

Figure 2 is a view similar to Fig. 1 showing the window regulator per se and with the window near its uppermost position;

Figure 3 is a cross section on the line 3—3 of Fig. 1, looking in the direction of the arrows;

Figure 4 is a cross section on the line 4—4 of Fig. 1, looking in the direction of the arrows;

Figure 5 is a cross section on the line 5—5 of Fig. 1, looking in the direction of the arrows; and

Figure 6 is a rear view showing the segment gear and the pinion for operating the regulator.

Referring to the accompanying drawings in which like numerals indicate like parts throughout the several views, the door or

other panel 10 of the car is provided with a pair of parallel walls 12 and 13, the walls 13 being assumed to be the outer wall of the car.

A window casing 15 having a sill 16 is provided in the car and mounts a window 17 therein, the mounting member for the window comprising a resilient cushion 18 mounted in a channel 20. The window is adapted to move from a lower position in which the window is below the sill 16 to an upper position in which the window contacts the upper edge of the casing 15; the movement being effected by a regulator, generally designated 25, and more particularly described as follows:

The regulator 25 is mounted on the wall 12 which forms a base for the regulator through a pair of brackets, generally designated 28 and 29, the operating members of the regulator comprising a pair of arms 31 and 33 pivotally mounted to the brackets 28 and 29 respectively and connected together by a link 35 which is pivotally connected to both of the arms 31 and 33.

The bracket 28 comprises a base 38 held parallel to the wall 12 by inturned portions or spacers 39, secured to the wall by a pair of outstanding ears 41 formed integrally with the spacers 39.

A segment gear 47 is formed on the outer periphery of the arm 31 and meshes with a pinion 48 pivotally mounted adjacent the upper end of the plate 38; the pinion 48 being driven by a hand crank 50 through a releasable spring clutch 51. The arm 31 is pivotally mounted through the center of the segmental gear 47 to the plate 38 through a suitable pin 44 which is herein shown as being riveted at both ends, and having a spacer 45 holding the arm 31 spaced from the plate 38. The handle 50 projects through the wall 12 as shown in Fig. 3 and into the interior of the car to permit a passenger to actuate it to raise or lower the window.

As best shown in Fig. 5, the bracket 29 comprises a base 55 which has a shoulder 56 containing a shaft 57, the shaft having a reduced portion 58 upon which the arm 33 is mounted, the arm 33 being retained on the

shaft 58 by means of a cotter pin 58' or equivalent holding means. The arrangement of the reduced portion 58 of the shaft 57 is such that the shoulder between the two is formed in the same plane as the plate 38. Since the pivotal points 44 and 58 are on the same plane and the segment gear is formed on the outer edge of the arm 31, the arm 33 is bent upwardly as shown at 59 so that it lies in the same horizontal plane with the end of the arm 31.

In order that the outer ends of the arms 31 and 33 be in the same plane, it is necessary to bend both arms 31 and 33 as shown at 60 and 61 respectively. It will be noted that, by properly positioning the bent out portions 60 and 61, that the arms 31 and 33 are permitted to cross intermediate the ends of their movement so that the regulator moves from a position shown in Fig. 1 to a position shown in Fig. 2, without difficulty.

The link 35 is pivotally connected to both the arms 31 and 33 and forms a driving connection, transmitting the motion from the arm 31 to the arm 33. By properly positioning the link 35, the outer ends of the arm can be made to move up and down so that they are always in a horizontal plane.

The ends of the arms 31 and 33 are provided with buttons 64 which slide in horizontal grooves 66 in a mounting channel 68, fixedly attached to the channel 20 by welding or other suitable means, the buttons 64 transmitting motion from the arms 31 and 33 through the channel 68 to the channel 20 and the window 17.

To install the regulator, the casing 15 is removed and the pane 17 pulled out of its casing and thence vertically past the upper limit of its normal movement. The buttons 64 may then be inserted through suitable enlarged ports 69 and the pane 17 lowered and the casing 15 replaced.

In operation, the handle 50 may be turned, turning the pinion 48 which actuates the segment gear 47 and raises or lowers the arm 31. Motion is transmitted from the arm 31 through the link 35 to the arm 33 causing a corresponding motion of the arm 33. The motion from the arms 31 and 33 is transmitted to the mounting channel 68 through the buttons 64 running in the groove 66 in the channel to raise or lower the window.

The clutch 51 is so arranged that it releases upon turning the handle in either direction, but grips its mounting member to restrain motion of the pinion 48 upon a force being exerted through the arm 31.

Having thus described the invention, it will be seen that there has been provided a relatively simple window regulator adapted to various uses and that it will be apparent that the regulator is of wider adaptability than to automobiles and can be used to regulate any window or for other analogous uses.

It is not, therefore, desired to limit the invention to the precise form herein shown and described, but only by the scope of the appended claims.

What is claimed as new and desired to secure by Letters Patent is:

1. In a window regulator of the character described adapted to raise and lower a window, a base, a first arm pivotally supported from said base, a second arm pivotally supported from said base, a link pivotally connected to said arms to transmit motion from one said arm to the other said arm, and means on said arms cooperating with means on the window to transmit motion from said arms to said window.

2. In a window regulator of the character described adapted to raise and lower a window, a base, a first arm pivotally supported from said base, a second arm pivotally supported from said base and having a segment gear formed on the outer periphery thereof, a pinion supported from said base meshing with said segment gear to move said arm, a link pivotally connected to both said arms to transmit motion from said second arm to said first arm, and means on the end of said arms cooperating with means on the window to raise or lower the window upon turning said pinion.

3. In a window regulator of the character described adapted to raise and lower a window, a base, a first arm pivotally supported from said base and comprising a main portion through which said pivotal support passes and an offset portion parallel to said main portion, a second arm pivotally supported from said base comprising a main portion and an offset portion, the main portion of said two arms and the offset portions of said two arms being in adjacent planes, means to transmit motion from said first arm to said second arm, means to transmit motion from said arms to the window, and means to acutate one of said arms whereby motion is transmitted from said last mentioned arm to said window.

4. In a window regulator of the character described adapted to raise and lower a window, a base, a first arm pivotally mounted on said base having a segment gear formed on the outer periphery thereof, a second arm pivotally supported from said base, said arm comprising main portions lying in one plane, and offset portions lying in an adjacent plane, means connecting said main portions to transmit motion from one said arm to the other said arm, a pinion rotatably supported from said base and meshing with said gear whereby movement of said pinion causes a corresponding movement of said gear, and means to transmit motion from the outer end of said offset portions to said window whereby movement applied to one of said arms is

transmitted through both of said arms to said window to actuate the window.

5. In a window regulator of the character described adapted to raise and lower a window, a base, a first arm pivotally supported from said base, a second arm pivotally supported from said base, a link pivotally connected to said arms to transmit motion from one said arm to the other said arm, means including a releasable clutch to move one of said arms, and means on said arms cooperating with means on said window to transmit motion from said arms to said window.

6. In a window regulator of the character described adapted to raise and lower a window, a base, a first arm mounted on said base and having a segment gear formed on the outer periphery thereof, a second arm pivotally supported from said base, said arms comprising main portions lying in one plane and offset portions lying in an adjacent plane, means connecting said main portions to transmit motion from one said arm to the other said arm, a pinion rotatably supported from said base and meshing with said gear, whereby movement of said pinion causes a corresponding movement of said gear, means mounted on the pivotal support of said pinion to prevent rotation of said pinion from a force applied to said arms, and means to transmit motion from the outer end of said offset portions to said window whereby movement applied to one of said arms is transmitted through both of said arms to said window to actuate the window.

In testimony whereof, I hereunto affix my signature.

STANLEY W. NICHOLSON.
